ATTORNEY

UNITED STATES PATENT OFFICE.

HERBERT O. PHILLIPS, OF WATERBURY, CONNECTICUT, ASSIGNOR TO
HOLMES, BOOTH & HAYDENS, OF SAME PLACE.

MACHINE FOR INSULATING ELECTRIC CONDUCTORS.

SPECIFICATION forming part of Letters Patent No. 285,672, dated September 25, 1883.

Application filed June 1, 1883. (No model.)

To all whom it may concern:

Be it known that I, HERBERT O. PHILLIPS, a citizen of the United States, residing at Waterbury, in the county of New Haven and State of Connecticut, have invented certain new and useful Improvements in Machines for Insulating Electric Conductors; and I do hereby declare the following to be a full, clear, and exact description of the invention, such as will 5 enable others skilled in the art to which it appertains to make and use the same.

My invention has for its object the ready coating of cotton-covered or braided wire with paint concurrently with the covering of the 15 same with braid.

The operation of my device is as follows, reference being had to the accompanying drawing, making part of this specification, and to the letters of reference marked thereon: The 20 wire *a* is passed up through the head of a braiding-machine, and a layer of cotton or other threads is placed upon the wire in the usual manner. The braiding-head, with spools, is indicated at *b*. The covered wire now passes in at the bottom of the paint-vessel *C* through a suitable packing, *d*. This vessel *C* and the manner in which the covered wire is painted or coated by means of it constitute the main feature of my invention. This 25 vessel *C* contains paint or other suitable coating material, and as the covered wire passes up through the same at *d* the paint therein saturates the braid covering. This arrangement admits of a second covering of braid being applied to the first covering of braid while the paint thereon is still wet, thereby forcing the paint into the interstices and pores of the braid and incorporating it thoroughly 30 therein.

Another feature of my invention is the arrangement of the friction-rollers *g g* in the machine. The office of these rollers is to move 40 the wire to the braiders. If these rollers are

so placed in the machine that they will clamp the wire after the braiding process, while the 45 braid is still wet with paint, they will, by reason of the pressure which they apply, give the product an oval or somewhat flattened shape; but if they are arranged in the machine so as to clamp the wire before braiding this 50 objection is overcome.

I do not claim covering braided wire with a layer of fibrous material, a coating of paint thereon, and a second layer of fibrous material upon the paint before the latter dries or sets, 55 for the same is an old and well-known process; but

What I do claim, and desire to secure by Letters Patent, is—

1. In a wire-braiding machine, the vessel *C*, 60 arranged to hold paint and to receive the braid-covered wire in a manner to cause it to pass through the paint, as herein shown and described.

2. In a wire-braiding machine having a 65 double set of braiders, the paint-holding vessel *C*, placed between the braiders in such manner that the wire, as it is braided in one set of braiders, will pass through the paint-vessel *C*, receive thereby a coating of the paint or other 70 suitable material thereon, and then receive from the second set of braiders a second broiding upon the painted surface of the first broiding while the paint is still wet thereon, substantially as shown and described.

3. In combination with the paint-vessel *C* and the braiding mechanism, the friction-rollers *g g*, arranged to impinge upon the wire before the same is braided, substantially as and for the purpose described.

In testimony whereof I affix my signature in presence of two witnesses.

HERBERT O. PHILLIPS.
